CENTER STOP-MOTION FOR LOOMS

Carl P. Bergstrom, Millbury, Mass., assignor to
Crompton & Knowles Loom Works, Worcester,
Mass., a corporation of Massachusetts

Application January 9, 1940, Serial No. 313,096

5 Claims. (Cl. 139—376)

This invention relates to center stop mechanisms for looms and it is the general object of the invention to provide a mechanism of this type wherein the knock-off dagger can move independently of the tines of the detecting fork.

In center stop motions as customarily made the tines of the detecting fork and the knock-off dagger are connected together positively by a link so that movement of one necessarily causes movement of the other. In the knocking-off operation the dagger is given an abrupt downward motion away from the knock-off lug on the shipper shaft or other part which is rocked when the loom is to be stopped. This motion of the dagger is communicated to the fork and the tines of the latter are forced upwardly against the cloth being woven. In the weaving of finer fabrics this upward motion of the fork is likely to damage the cloth.

It is an important object of my present invention to make the dagger carrier and the fork controller in two parts which are caused to move together in one direction by a positive connection when the fork is moved to detecting position, but wherein the dagger carrying part can move relatively to the second part attached to the fork so that the abrupt downward motion of the dagger will not be transmitted to the fork.

In center stop motions as customarily made there is a vertically reciprocating rod which attuates a positive link connection between the filling fork and a pivoted part on the lay which has direct engagement with the rod. It is another object of my invention to preserve this positive link connection while at the same time permitting independent movement of the dagger with respect to the link connection for the reasons already mentioned.

In certain looms wherein the take-up roll is relatively high there is danger that the dagger will engage the roll if permitted to move too far down on the forward stroke of the lay during a loom stopping operation. It is another object of my present invention to provide a stop for the dagger carrying part of the invention which will prevent engagement of the dagger with the take-up roll but be so located as to have no effect on the filling fork or the parts positively connected thereto. By this arrangement the more sensitive detecting part of the stop motion is spared the stock incident to the abrupt stopping of the dagger in its downward motion.

With these and other objects in view which will appear as the description proceeds, my invention

resides in the combination and arrangement of parts hereinafter described and set forth.

In the accompanying drawing, wherein a convenient embodiment of my invention is set forth,

Fig. 1 is a vertical section through a portion of the loom equipped with my invention and showing the lay in rear position with the filling fork raised.

Fig. 2 is a view similar to Fig. 1 but wherein the lay has moved to beat-up position and the fork has descended on its detecting stroke.

Fig. 3 is a detail horizontal section on line 3—3 of Fig. 1, on an enlarged scale.

Fig. 4 is a rear elevation taken in the direction of arrow 4, Fig. 3.

Fig. 5 shows parts of the structure shown in Fig. 1 on an enlarged scale, and

Fig. 6 is a view similar to a portion of Fig. 5, parts being in section to illustrate the relationship between the dagger carrier and the fork controlling parts.

Referring to the drawing, the loom frame 10 has a breast beam 11 under which is mounted a shaft 12 to be rocked when the loom is to be stopped. Secured to the shaft is a lug 13 having a knock-off notch 14 above which is an overhanging cam 15 which acts to disengage the dagger 16 from the notch 14 during the latter part of a knocking-off stroke of the loom.

The lay 20 has a reed 21 along which travels a shuttle S between top and bottom warp sheds W and W'. Depending from the front face of the lay is a bracket 25 in which is mounted a small shaft 26 to which is secured a plate 27. The latter is pivotally connected as at 28 to a depending rod 29 in the usual manner. A barrel 30 secured to the shaft 26 carries the tines 31 which comprise the detector fork.

The lower end of bracket 25 is extended as at 35 to receive and guide the upper end of a rod 40 or actuator 36 the lower end of which not shown herein is customarily pivoted to a stud eccentric with respect to the axis of the lay so that on the back stroke of the lay the rod 36 is given an upward motion relatively to the bracket 25, 45 while on the forward lay stroke the rod moves downwardly with respect to the bracket. On its up stroke rod 36 engages an arm 37 pivotally mounted on a stud 38 secured to bracket 25 and having a pivotal connection 39 with the lower end 50 of rod 29.

Except for modifications in arm 37 and the mounting for dagger 16 to be described, the parts thus far set forth are constructed and operate in the usual manner, rod 36 lifting the filling fork 55

on the backward stroke of the lay by a force transmitted positively through arm 37, rod 29, plate 27 and shaft 26. The connections between link 29 and the parts to which it is pivotally attached have proved very satisfactory in long continued use, due partly to the fact that rod 36 engages arm 37 without having direct contact with the link 29.

In carrying my present invention into effect 10 I separate the arm 37 from the dagger by providing a dagger carrier 41 into which the dagger 16 projects to be held by a set screw 42, as indicated for instance in Fig. 5. The dagger carrier has the rear end thereof forked as at 43 to receive a relatively narrow bearing 45 on arm 37. The forks 43 extend rearwardly and overhang a portion of the arm 37 as indicated in Figs. 3 and 6. A torsion spring 50 surrounds a part of the stud 38, one end of the spring being held to the 15 stud and the other end being caught under the set screw 42. The effect of the spring is to hold the rear parts of the forks 43 against the broadened part of arm 37, but the spring will permit the dagger part 41 to move in a counter-clockwise direction around stud 38 to move the forks 43 away from arm 37.

In operation, rod 36 will reciprocate vertically as already described and in its upward motion will engage arm 37 to transmit a positive force 20 through rod 29 to the filling fork. At the same time arm 37 acts on the forks 43 to rock the dagger and its carrier in a downward direction to the position indicated in Fig. 1. So long as weft is present in the warp shed the tines of the fork will be supported in a relatively high 25 position and the dagger will be prevented from engaging the lug 13 on the forward stroke of the lay. When the weft thread is broken, however, the fork falls to low position due to action 30 of spring 50 and the dagger will be raised to a position where continued forward motion of the lay will cause it to enter the notch 14. Still further forward motion of the lay causes the dagger to rock shaft 12 in a clockwise direction 35 in Fig. 1, thereby bringing the shoulder 15 against the dagger to disengage the latter and permit continued motion of the lay.

At the instant of disengagement of the dagger 40 from the lug the shoulder gives the dagger a quick downward motion which would have the effect in center stop motions as heretofore constructed of causing upward motion of the filling fork. Because of the fact, however, that the dagger is mounted on a carrier movable independently of the arm 37, the latter has no force 45 communicated to it from the dagger which would tend to raise the fork. During this downward motion of the dagger the forks 43 move away from arm 37 and the latter together with the rod 29 and the fork remain substantially unchanged. When the spring acts to return the 50 dagger to its normal up position the forks 43 again engage arm 37 to lower the fork 31. So long as the weft remains intact the rising and falling of the rod 36 is accompanied by a corresponding rocking of the dagger and the filling fork as though these parts were a single unit, being held together by the spring. It is only 55 when the dagger is given a downward motion that it becomes relatively disconnected from the filling fork so that the latter will not be affected or moved by the dagger.

In certain looms having a relatively high take-up roll there is danger that if the dagger is depressed too low the forward motion of the lay 60

will drive the dagger into the take-up roll, thereby damaging its surface. In order to prevent excess down motion of the dagger I provide an adjustable stop shown more particularly in Figs. 1, 2 and 5 comprising an extension 55 of the bracket 5 25 and a stop screw 56 therein mounted for vertical adjustment and held in position by a lock nut 57. The head 58 of the screw is positioned under the dagger carrier 41 a sufficient distance to allow the dagger to clear the knock-off lug 13 10 but prevent it from coming in contact with the take-up roll indicated at T in Fig. 2.

From the foregoing it will be seen that I have provided a center stop motion wherein the dagger is capable of a downward motion independently of the filling fork due to the fact that the dagger carrier forks 43 move away from arm 37 without tendency to move the latter. It will further be seen that under normal conditions the spring and the forks 43, by their engagement with 20 the arm 37, hold these two parts yieldingly together. Furthermore, the arm and fork 31 are positively connected at all times through the link 29, a condition which experience proves to be 25 advantageous. It will further be seen that the independently movable dagger carrier 41 is restricted in its downward motion by the adjustable stop screw 56.

Having thus described my invention it will be seen that changes and modifications may be 30 made therein by those skilled in the art without departing from the spirit and scope of the invention and I do not wish to be limited to the details herein disclosed, but what I claim is:

1. In a filling stop motion for a loom having a lay on which is mounted a rotatable support secured to a filling fork, the lay having a dagger for engagement with loom stopping mechanism the effect of which is to give the dagger a downward motion incident to a loom stopping operation, and the loom having an actuator which reciprocates vertically with respect to the lay, a dagger carrier pivotally mounted on the lay, a spring having one end fixed with respect to the lay and having the other end connected to the carrier and tending to raise the latter and the dagger relatively to the lay, an arm pivotally mounted on the lay, a link pivoted to the arm and connected to the rotatable support for the filling fork, and the dagger carrier and arm having mutually engaging parts to transmit a force derived from the spring through the dagger carrier to the arm in a direction to lower said arm and the filling fork during descent of the actuator, said parts causing the dagger carrier and dagger to be lowered when said arm and link are raised by upward motion of the actuator, said carrier when given said downward motion incident to a loom stopping operation moving pivotally independently of the arm and filling fork 40 to cause separation of said parts and thereby prevent the transmission of force from the dagger 45 to the filling fork.

2. In a filling stop motion for a loom having a lay on which is mounted a rotatable support to which is secured a filling fork, the lay having a dagger for engagement with loom stopping mechanism the effect of which is to give the dagger a downward motion incident to a loom stopping operation, the loom having also an actuator which reciprocates vertically with respect to the lay, a stud fixed to the lay, a dagger carrier pivoted on the stud, a spring surrounding the stud having one end thereof secured to the stud and having the other end attached to the 50 55 60 65 70 75 80 85 90 95

- dagger carrier, said spring tending to raise the dagger and dagger carrier, an arm also pivoted on the stud and positioned for engagement with the actuator, a rigid link connecting the arm and the rotatable support for the filling fork to be raised to lift the filling work when the actuator rises to raise said arm, the dagger carrier and arm having mutually engaging separable parts constructed to transmit a force derived from the spring through the dagger carrier to the arm to lower the latter and the filling fork during descent of the actuator, said parts having a relative movement away from each other when the dagger is given said downward motion incident to a loom stopping operation and the carrier being movable pivotally on the stud and downwardly independent of the arm and the filling fork.
3. In a filling stop motion for a loom having a lay on which is mounted a rotatable element secured to a filling fork, the lay having a dagger for engagement with loom stopping mechanism the effect of which is to give the dagger a downward motion incident to a loom stopping operation and the lay having fixed thereto a pivotal support and the loom having an actuator which reciprocates vertically with respect to the lay during loom operation, a carrier for the dagger pivoted on the support, a spring having one end fixed with respect to the support and having the other end thereof attached to the dagger carrier, said spring tending to raise the dagger and dagger carrier and yielding to permit the aforesaid downward motion of the dagger, an arm also pivoted on the support and separate from the dagger carrier and positioned for engagement with the actuator, a link connecting the arm to the rotatable element for the filling fork to cause the filling fork to rise when the arm is raised by upward motion of the actuator, and the dagger carrier and arm having mutually engaging parts through which the spring transmits a force tending to lower the arm and lift the dagger carrier during descent of the actuator, said parts having a relative movement away from each other when the dagger is given the aforesaid downward motion incident to a loom stopping operation to prevent transmission of force from the dagger to the arm and link and filling fork.
4. In a filling stop mechanism for a loom having a lay provided with a filling fork secured to a rotatable element mounted on the lay and the latter having a dagger for engagement of loom stopping mechanism the effect of which is to give the dagger a downward motion incident to a loom stopping operation and the loom having an actuator which reciprocates vertically with respect to the lay, a pivotal support fixed to the lay, two separate members both of which are pivoted on the support, the first member carrying the dagger, a spring having one end fixed with respect to the support and having the other end fixed to the first named dagger carrying member and acting to exert an upward force on the latter, the second member being placed for direct engagement with the reciprocating actuator, a link connecting the second member to the rotatable element to lift the filling fork when upward motion of said actuator raises the second member, and means carried by one of the members to engage the other member to cause said second member to move downwardly by a force derived from the spring when the latter raises the first member during descent of the actuator, said first member being movable downwardly against the action of the spring independently of motion of the second member when the dagger has the aforesaid downward motion incident to a loom stopping operation, whereby said downward motion of the dagger is ineffective to raise the second member and the filling fork.
5. In a filling stop mechanism for a loom having a lay provided with a filling fork secured to a rotatable element mounted on the lay, the lay having a dagger for engagement with loom stopping mechanism the effect of which is to give the dagger a downward motion incident to a loom stopping operation and the loom having an actuator which reciprocates vertically with respect to the lay, a pivotal support fixed to the lay, a spring having one end fixed to the support, a dagger carrier pivotally mounted on the support and connected to the other end of said spring to be raised by the latter, an arm also pivoted on the support and positioned to be raised by the actuator, means connecting the arm and the rotatable element to cause said rotatable element to turn in a direction to raise the filling fork when said arm is raised by upward motion of the actuator, said carrier having a part to engage the arm to lower said arm by a force derived from the spring when the latter raises the carrier during descent of the actuator, said carrier being movable angularly on the pivotal support and said part on the carrier moving away from the arm when the dagger has the aforesaid downward motion incident to loom stopping operation to disconnect the dagger from the arm and filling fork.
